United States Patent Office

Des. 179,880
Patented Mar. 19, 1957

179,880

VACUUM BOTTLE

Carl Bramming, Nashville, Tenn., assignor to Aladdin Industries, Incorporated, Nashville, Tenn., a corporation of Illinois

Application December 22, 1955, Serial No. 39,450

Term of patent 14 years

(Cl. D58—8)

Fig. 1 is a perspective view of a vacuum bottle, showing my new design.

Fig. 2 is a fragmentary view of the surface ornamentation thereof taken on an enlarged scale.

I claim:

The ornamental design for a vacuum bottle, substantially as shown.
